AIR FILTER FOR GAS HEATERS

Benjamin C. Bartlebaugh, Wheeling, W. Va.

Application January 6, 1934, Serial No. 705,590

2 Claims. (Cl. 183—49)

The present invention is directed to improvements in air filters for use in connection with gas heaters of the furnace type, that is to say a heater wherein the air is compelled to flow through passages about a combustion chamber within the casing.

The primary object of the invention is to provide novel means to prevent soot and dust drawn into the heater with the incoming air from being injected into the room or space in which the heater is located, the construction being such that the ejected air will be effectively filtered in order that only clean air will be discharged.

Another object of the invention is to provide a device of this character wherein the filtering medium can be easily and quickly removed from the heater in order that all soot and dust collected may be removed therefrom in any manner seen fit.

With these and other objects in view, this invention resides in the novel features of construction, formation, combination and arrangement of parts to be hereinafter more fully described, claimed and illustrated in the accompanying drawings, in which:

Figure 1 is a perspective view of the heater.

Figure 2 is a longitudinal sectional view through the same.

Figure 3 is a vertical central sectional view.

Figure 4 is a sectional view on line 4—4 of Figure 3.

Figure 5 is a bottom plan view of the top plate of the heater.

Referring to the drawings, 1 designates a casing comprising inner and outer laterally spaced walls 2 and 3, which define an air chamber 4, the inner wall constituting in conjunction with the top 5 a combustion chamber 6, said top being inclined downwardly in a direction to the front opening 7 of the casing.

A baffle plate 8 is supported in the combustion chamber 6 below the top 5 and has its rear edge spaced from the inner wall 2, as clearly shown in Fig. 3 in order to provide a passage 9.

The top 10 of the casing is provided with an opening 11 through which the heated burn-over gases are discharged.

Spaced from the back wall 2 is a fire-wall 12 having a series of openings 13 formed therein, the purpose of which will appear later.

The lower edge of the fire-wall abuts a plate 14 constituting a bottom for the burner 15, said burner including a breast plate 16 having a plurality of jets 17, there being located under the plate 16 a gas discharge nozzle 18, the same being

connected with a source of supply through the pipe 19.

Air from the room is admitted to the casing through the openings 20 formed in the sides and back of the outer wall 3 and openings 21 formed in the front plate 22.

A deflector plate 23 is supported by the casing 1 and is extended downwardly to the front opening 7, as clearly shown in Fig. 3.

It will be observed that the inner wall 2 is of less length than the outer wall 3 in order that air entering the openings 20 and 21 will pass freely into the chamber 4 and be heated by the walls of the combustion chamber 6.

Secured to the top 10 and transversely of the opening 11 thereof are parallel spaced channel bars 24 to which are secured the bolts 25. The bolts 25 serve to detachably secure the plate 26, constituting a supplemental top for the casing, spaced above the opening 11 to permit heated air 20 to pass freely from the casing. Ornamental knobs 27 removably engage the bolts 25 and serve to retain the plate 26 in place.

The plate 26 is provided with a depending marginal flange 28, and removably bolted to the under surface of the plate are longitudinally and transversely extending metallic strips 29 and 30, respectively, which serve to clamp the elongated masses or sections of steel wool 31 and 32 firmly to said plate, as clearly shown in Fig. 5. The 30 masses are of such depth that they will depend from the plate and surround the opening 11 of the top 10 in order that the heated air passing through said opening will also pass through the masses, thereby effectively filtering the out rushing air. The masses are shown spaced slightly above the top 10, but if desired they may rest thereon. A plate 33 is secured to the front of the plate 26 and extends downwardly a sufficient distance to conceal the opening between the plate 26 and top 10.

When gas from the burner 15 is ignited the hot unburned gases will rise and be directed rearwardly by the baffle plate 8 and top 5, and thence rapidly downwardly into the passage 13' behind 45 the fire-wall 12. At the same time fresh air will be drawn through the opening 7 into the passage 9 and will be directed downwardly into the passage 13'. The hot non-consumed gases will rapidly commingle with the air in the passage 13' and 50 with the air drawn into the passage 9. This mixture of air and gas is blown through the openings 13 with considerable velocity, and this mixture is directed under pressure into the ascending flame of the burner, whereby the unburned gases 55

are positively burned to eliminate the discharge of unburned gases into the room. This cycle of operation takes place as long as the burner is ignited, and the discharge of obnoxious odors and dangerous gases is positively eliminated.

What is claimed is:—

1. A device of the class described comprising a casing having an inlet and having an opening in its top, spaced bars bridging the opening, bolts 10 extending upwardly from the bars and having shoulders thereon, a top plate removably engaged on the bolts and supported by said shoulders above the casing top, filtering masses, clamping strips secured to the under surface of the top 15 plate and adapted to secure the masses to said top plate about the periphery thereof, whereby

the masses will be removable with the top plate, said masses depending from the top plate to surround the walls of the opening in the casing top.

2. A device of the class described comprising a casing having an air inlet and having an opening in its top, bolts carried by the casing and extending upwardly from the opening, a top plate removably engaged on the bolts and supported thereby above the casing top and defining with said top an outlet passage, elongated filtering 10 masses, and means to secure the masses to the under side of the top plate about the periphery thereof, whereby said masses are interposed in said outlet passage, and are removable with the top plate. 15

BENJAMIN C. BARTLEBAUGH.
